SHUTTLE FILLING GUIDE

Application filed January 18, 1932. Serial No. 587,229.

- This invention relates to shuttles of the type commonly used in looms and is concerned more particularly with a shuttle having a novel yarn guide used with a tensioning means and so constructed that wear on the surfaces of the guide and tensioning device is distributed and prevented from becoming localized so as to produce grooves or projections.
- 10 In shuttles as now ordinarily constructed, the yarn passes from the cop or bobbin in the shuttle through a tension trap and thence out of the shuttle through an eyelet. As the shuttle is thrown in opposite directions, 15 the yarn bears first against one side and then the other of the eyelet. These eyelets are ordinarily circular and the yarn tends to cut grooves in the opposite sides thereof by continuously bearing against localized areas.
- 20 The tension trap which is located within the shuttle usually consists of two members between which the yarn passes and as the wear from the yarn is continuously on the same area, grooves also tend to wear in the yarn 25 contacting members of this device. The amount of wear depends to some extent on the type of yarn which the shuttle carries and some yarns, such as jute, are particularly harmful in their effects on the surfaces 30 with which they contact in both the tension device and guide. Any wear in the tension trap causes the tension on the filling to vary, producing imperfect edges and uneven weaving in the fabric and constant attention is 35 required to prevent the production of imperfect fabric. When the shuttle is used in a loom for producing pile fabrics, the varying tension also produces a varying binding action on the pile tufts. Localized 40 wear resulting in slotting or cutting of the yarn contacting surfaces in the guide or tension trap causes the filling to break and this necessitates stopping the loom to repair the filling.
- 45 The present invention is directed to the provision of a shuttle having a novel filling guide so constructed as to prevent localized wear both in the guide and in the tension trap, and thus prevent the formation of projections and indentations in the contacting 50 surfaces, by distributing the wear from the yarn over a greater area. The new guide is formed to provide a passage for the filling in the shape of a slot instead of a circular hole as heretofore provided and the slot is 55 so shaped that the drawing of yarn from the shuttle during weaving causes the yarn to move back and forth across the slot, thus spreading the wear over a considerable area and preventing local wear and the formation 60 of grooves or ridges. This movement of the filling across the guide slot is continued back to the tension device and the filling moves back and forth across a substantial wear surface of the latter during 65 the shuttle movement. As a result of the movement of the filling described, localized wear both in the guide and tension trap are prevented and, since the surfaces which contact with the filling have a substantial extent, not only is grooving of the eyelet and trap avoided, but also the life of the parts 70 is greatly lengthened.
- For a better understanding of the invention, reference may be had to the accompanying drawing in which,
- Fig. 1 is a top plan view of a standard form of shuttle provided with my invention;
- Fig. 2 is a longitudinal side sectional view of the shuttle illustrated in Fig. 1 with the 80 cover removed;
- Fig. 3 is an enlarged bottom plan view of a portion of the shuttle illustrated in Fig. 1;
- Fig. 4 is a top plan view of the guide;
- Fig. 5 is a view in side elevation;
- Fig. 6 is a bottom plan view of the guide; and
- Figs. 7 and 8 are sectional views on the lines 7-7 and 8-8 of Fig. 6.
- In the illustrated example, a shuttle constructed according to the principles of this invention comprises a body 10 having a recess 11 therein which contains a package or cop of yarn 12 and a tension device 13 consisting of a pivoted plate 14 resiliently urged against a crossbar 15 by a spring 16 so as to tension the yarn which passes between the plate and the crossbar. The pivoted plate 14 carries a yarn guiding member 17 which prevents the 90 yarn from slipping off of the plate. The 95 100

recess 11 in the shuttle body is closed by a cover 18 which passes over cross rods 19 and is secured in place by hooked-shaped member 20. The yarn passes from the cop 12 between the pivoted plate 14 and the crossbar 15 and out of the shuttle through a guide member 20 which extends through the bottom of the shuttle and has an opening 22 therethrough for the passage of the yarn.

10 The guide member 20 is preferably formed of porcelain but may be of steel, brass or other wear-resisting material and may, if desired, be an integral part of the shuttle body rather than a separate member embedded therein. The opening 22 through which the yarn passes is in the form of a slot which extends transversely of the shuttle at its inner end and twists inside of the guide member so that it is at an angle to a line transverse of the shuttle at its outer end.

15 As will be seen from Figure 3, when the yarn is pulled from the shuttle towards the forward end as is shown in full lines, the yarn will tend to move towards one end 24 of the slot 22 and when the yarn is pulled from the shuttle towards the rear end thereof, the yarn will tend to move towards the opposite end 25 of the slot. In the operation of the shuttle with the new guide on a loom, the yarn is drawn first in one direction and then in the other, and the yarn moves back and forth across the slot and prevents wear from occurring in a localized area and hence prevents the formation of grooves, slots or projections.

20 The inner end of the guide slot 22, lying transverse of the shuttle, permits the yarn at this end to follow the movement of the yarn at the other end of the slot, and as the tension trap is located closely adjacent to the guide, the transverse movement of the yarn takes place in this device also and localized wear is eliminated here in a similar manner.

25 Having thus described my invention, what I claim is:

1. In a shuttle, a receptacle for a yarn package and an elongated slot in the body of the shuttle through which the yarn is fed, said slot having a portion which is inclined to the direction of shuttle movement.

2. In a shuttle, a receptacle for a yarn package and an elongated slot in the body of the shuttle through which yarn is fed, the outer end of said slot being inclined to the direction of shuttle movement.

3. In a shuttle, a receptacle for a yarn package and an elongated slot in the body of the shuttle through which yarn is fed, the outer end of said slot lying transverse to the long axis of the shuttle.

4. In a shuttle, the combination of a receptacle for a yarn package and an elongated

slot in the body of the shuttle through which yarn is fed, the outer end of said slot being inclined to the direction of shuttle movement, and a tension device in said shuttle located adjacent the inner end of said slot.

5. In a shuttle, the combination of a receptacle for a yarn package and an elongated slot in the body of the shuttle through which yarn is fed, the outer end of said slot being inclined to the direction of shuttle movement, and the inner end of said slot lying transverse to the long axis of the shuttle, and a tension device in said shuttle comprising friction surfaces bearing against the yarn and located adjacent the inner end of said slot.

6. In a shuttle, the combination of a receptacle for a yarn package and an elongated slot in the body of the shuttle through which yarn is fed, the outer end of said slot being inclined to the direction of shuttle movement, and a tension device comprising a plate over which the yarn is drawn lying adjacent the inner end of said slot whereby the movement of the yarn across the slot moves the yarn across the plate of the tension device.

7. In a shuttle, the combination of a receptacle for a yarn package and an elongated slot in the body of the shuttle through which yarn is fed, the outer end of said slot being inclined to the direction of shuttle movement, and the inner end of said slot lying transverse to the long axis of the shuttle, and a tension device comprising a plate over which the yarn is drawn lying adjacent the inner end of said slot whereby the movement of the yarn across the slot moves the yarn across the plate of the tension device.

8. In a shuttle, the combination of a shuttle body containing a receptacle for a yarn package, a block embedded in the shuttle body having an elongated slot through which filling yarn is drawn from the shuttle, the outer end of said slot being inclined to the direction of shuttle movement.

9. In a shuttle, the combination of a shuttle body containing a receptacle for a yarn package, a porcelain block embedded in the shuttle body having an elongated slot through which filling yarn is drawn from the shuttle, the outer end of said slot being inclined to the direction of shuttle movement.

10. In a shuttle, the combination of a shuttle body having a receptacle for a yarn package, a tension device within said shuttle body comprising cooperating members between which yarn from said package passes, and an opening in the shuttle body for passage of said yarn, said opening having a transversely elongated outer end lying at an angle to the direction of shuttle movement.

11. In a shuttle, the combination of a shuttle body having a receptacle for a yarn package, a tension device within said shuttle body comprising a pair of members between which yarn from said package passes, said members

having surfaces of substantial length extending across the shuttle body, said yarn passing in contact with said surfaces, and an opening in the shuttle body for passage of said yarn, said opening having an elongated inner portion lying across the shuttle body and an elongated outer portion inclined to the direction of shuttle movement.

5 In testimony whereof I affix my signature.
